UNITED STATES PATENT OFFICE.

JOHN EDW. OGDEN, OF CORNWALL, NEW YORK.

BOLT-ANCHOR.

1,305,001.

Specification of Letters Patent. Patented May 27, 1919.

Continuation in part of application Serial No. 878,844, filed December 24, 1914. This application filed September 28, 1917. Serial No. 193,625.

To all whom it may concern:

Be it known that I, JOHN EDWARD OGDEN, a citizen of the United States of America, and a resident of Mountainville, town of

5 Cornwall, Orange county, and State of New York, have invented certain new and useful Improvements in Bolt-Anchors, of which the following is a specification, reference being had to the accompanying drawings, forming

10 a part thereof.

My invention relates to bolt anchors and particularly to such as comprise folded metal parts and are adapted to be formed from sheet metal.

15 In my copending application Serial No. 878,844 filed Dec. 24, 1914, of which this application forms a continuation in part, I have shown, described and claimed broadly, a bolt anchor comprising a tubular metal member having a tapered bore and having the thickness of its walls increased by folding the metal together near the smaller part of the tapered bore.

20 My present invention pertains in general to bolt anchors of the same kind and has for one object to provide a tubular anchor having a substantially cylindrical constricted bore at one part, the walls of the constricted bore being increased in thickness 25 by folding or wrapping the metal therein. Two or more thicknesses of metal are thus formed in close contact and the exterior of the anchor is shaped to fit closely to a cylindrical hole.

30 Another object is to provide an anchor of the aforesaid character having a two-part shell and wedge blocks for forming the members of the shell apart.

35 In order that my invention may be thoroughly understood, I will now proceed to describe the same in the following specification, and then point out the novel features thereof in appended claims.

40 Referring to the drawings:

45 Figure 1 is an elevation of a bolt anchor arranged and constructed in accordance with my invention and constituting one embodiment thereof.

50 Fig. 2 is a transverse sectional view taken on the line 2-2 of Fig. 1.

Fig. 3 shows the anchor of the preceding figures developed into a single plane and illustrates a method of forming the anchor from sheet metal.

55 Fig. 4 is a view corresponding to Fig. 1 of

a modified anchor which also constitutes an embodiment of my invention.

Fig. 5 is a longitudinal section of the anchor shown in Fig. 4.

Figs. 6 and 7 are transverse sections, taken 60 respectively on the lines 6-6 and 7-7 of Fig. 4, and

Fig. 8 is a development corresponding to Fig. 3 of one member of the anchor shown 65 in Fig. 4.

Still another modification of my invention is shown in Figs. 9 to 13 inclusive which correspond respectively to Figs. 4 to 8, the transverse sections shown in Figs. 11 and 12 being taken on the lines 11-11 and 12-12 70 of Fig. 10.

Referring first to Figs. 1, 2 and 3, the bolt anchor here shown comprises a tubular body 15 composed of a part 16 having a tapered bore and a part 17 having a substantially 75 cylindrical constricted bore. The part 17 throughout the greater part of its length has the thickness of its walls increased by an overlapped portion of metal designated 18. In the particular modification under discussion the tapered part 16 and the inner thickness of the part 17 are formed from the rectangular body part 19 of the sheet metal plate shown in Figs. 3, and the overlapped outer layer is formed from the projection 20 80 which is folded or wrapped upon the inner layer.

The arrangement of parts is such that the outside diameter of the thickened part of the anchor is substantially equal to the largest 90 diameter of the tapered part 16. Consequently the anchor is adapted to fit closely into a cylindrical hole before it is expanded.

The expansion of the anchor is facilitated by incisions 21 and the tapered part 16 is 95 provided with diamond-shaped notches 22 to receive projections or lugs 23 which extend laterally from the taper plug expander 24 which prevent it from rotating and assist in the expansion of the device. The expander 100 has a tapped hole 25 to receive a threaded bolt in a well known manner.

The anchor instead of having a single tapered part and a single expander may be formed with a tapered part at each end, the 105 cylindrical walls of which are increased in thickness becoming the middle part of the anchor and a second taper plug expander being utilized.

In Figs. 4 to 8 inclusive to which special 110

- reference may now be had, I have shown a double end expander of a slightly modified construction which comprises a tubular body 26 formed of two parts which are identical 5 and which are preferably held together by spring rings 27 or other suitable means which is intended to keep the parts of the device together until it is used and may be replaced by any suitable means.
- 10 Fig. 8 shows one of the parts of the anchor developed into a single plane and the wings or projections 28 are folded back to increase the thickness of the walls at 29 as clearly shown in Fig. 5. The parts of the shell are 15 shaped so that the bore is tapered at each end and is constricted intermediate its ends, the walls being thickened at the constricted part. The folding or lapping of the metal is clearly illustrated in Fig. 6 and the outside diameter of the anchor at the thickened part is substantially equal to the largest diameter of the tapered parts. Consequently 20 the anchor fits closely into a cylindrical hole, as illustrated in Fig. 5.
- 25 The tapered parts of the shell which are designated 30 are provided with notches 31 forming recesses which are adapted to receive lugs or projections 32 33 from taper plug expanders 34 and 35.
- 30 The plug 34 has a tapped hole 36 to receive the screw-threaded end of the bolt 37 while the plug 35 has a clearance hole 38 through which the bolt extends loosely.
- The arrangement of parts is such that 35 when a collar 40 or a part of the member to be secured to the wall is forced inwardly by tightening the bolt 37, the taper plugs 34 and 35 are drawn together, forcing the members of the anchor apart and causing 40 it to very securely grip the surrounding wall.
- Referring to Figs. 9 to 13, inclusive, in which like parts are designated by the same reference characters, the anchor here 45 shown differs from that shown in Figs. 4 to 8 inclusive, in that the bore of the shell tapers inwardly to the center and the projections or wings 42 which are folded or lapped onto the central part of the anchor 50 to increase the thickness of the walls at the constricted middle part, are preferably tapered as shown in Fig. 13.
- A pair of tapered plugs or expanders 43 and 44 correspond respectively to the expanders 34 and 35 and are similarly provided with lugs 45 and 46 corresponding to the lugs 32 and 33 coöperating with notches 47 which prevent the expanders from turning and help to spread the members of the shell apart when a bolt is inserted and tightened as shown in Fig. 9.
- While I have shown structures formed of uniform thickness metal and while I prefer to employ ordinary sheet metal, my invention is not limited in this regard and

cast or malleable metal may be employed if desired.

Various modifications may be effected within the spirit and scope of my invention, and I intend only such limitations as are indicated in the appended claims. 70

What I claim is:

1. A bolt anchor comprising a tubular metal body constructed with a constricted part intermediate its ends, said constricted part having its walls thickened by overlapping of the metal upon itself. 75
2. A bolt anchor comprising a tubular metal body constructed with a cylindrical part of reduced size having its walls increased in thickness by folding the metal together laterally. 80
3. A bolt anchor comprising a tubular metal body constructed with a cylindrical part of reduced size intermediate its ends, the walls of said part being increased in thickness by overlapping of metal. 85
4. A bolt anchor comprising a tubular metal body comprising a cylindrical part of reduced size intermediate its ends and having a tapered bore at each end, the walls of said cylindrical part being increased in thickness by folding the metal together. 90
5. A bolt anchor comprising a tubular member composed of a plurality of parts coöperating to form a tapered bore, one or more of said parts having the thickness of its walls increased near the smaller part of the tapered bore by folding the metal together laterally. 95
6. A bolt anchor comprising a plurality of parts coöperating to form a tubular metal member having a cylindrical portion of reduced size, at least one of said parts having its walls increased in thickness at the reduced portion of the anchor by folding the metal together laterally. 100
7. A bolt anchor comprising a plurality of parts coöperating to form a tubular metal member having a cylindrical portion of reduced size and tapered bores at its ends, at least one of said parts having its walls increased in thickness at the reduced portion of the anchor by folding the metal together. 105
8. A bolt anchor comprising a plurality of rectangular metal sheets each having a projection and rolled into tubular form with the projection wrapped onto the tubular body at one part. 110
9. A bolt anchor formed of sheet metal having a tubular body comprising two similar semi-cylindrical members, each having a central portion of reduced internal diameter, in which its walls are thickened by folding the sheet metal back on itself. 115
10. A bolt anchor formed of sheet metal having a tubular body comprising two similar semi-cylindrical members, each having flaring end portions and an intermediate portion in which its walls are thickened by 120
11. A bolt anchor formed of sheet metal having a tubular body comprising two similar semi-cylindrical members, each having flaring end portions and an intermediate portion in which its walls are thickened by 125
12. A bolt anchor formed of sheet metal having a tubular body comprising two similar semi-cylindrical members, each having flaring end portions and an intermediate portion in which its walls are thickened by 130

5 folding the sheet metal back on itself, said members being adapted to coöperate to form a hollow member with the central portion of its opening restricted and tapering outwardly toward its ends.

11. A bolt anchor formed of sheet metal having a tubular body comprising two similar semi-cylindrical members, each consisting of a punching or stamping having flaring ends and lateral projections, said lateral projections being folded back on the central portion of the member, whereby the anchor has an opening tapering outwardly from the center and thickened walls at the 15 restricted part of the opening.

12. A bolt anchor formed of sheet metal

having a tubular body comprising two similar semi-cylindrical members, each having a central constricted portion in which its walls are thickened by folding the sheet 20 metal back on itself, expansion members in the respective ends of said tubular body, and wedge projections from said expansion members, said semi-cylindrical members being constructed with notches between 25 which said projections are received.

In witness whereof, I have hereunto set my hand this 26th day of September, 1917.

JOHN EDW. OGDEN.

Witness:

I. B. MOORE.
